UNITED STATES PATENT OFFICE.

ELIAS S. HUTCHINSON, OF BALTIMORE, MARYLAND, ASSIGNOR TO HIMSELF AND HUGH L. McAVOY, OF SAME PLACE.

IMPROVED APPARATUS FOR GENERATING STEAM.

Specification forming part of Letters Patent No. 58,727, dated October 9, 1866.

To all whom it may concern:

Be it known that I, ELIAS S. HUTCHINSON, of the city and county of Baltimore, and State of Maryland, have made new and useful Improvements in the Application of Carbureters to Steam-Generators, &c.; and I do hereby declare the following to be a full, clear, and exact description of the nature, construction, and operation of the same, sufficient to enable one skilled in the art to which they are allied to construct and use the same, reference being had to the accompanying drawings, in which my improvement is shown as applied to a locomotive steam-engine, and in which—

Figure 1 is a vertical and longitudinal section on the line xx , Fig. 2. Fig. 2 is a longitudinal section of the same on the irregular line yy , Fig. 1. Fig. 3 is a vertical transverse section on the line zz , Fig. 1.

The invention consists in combining with the moving parts of the machinery an air-forcing apparatus to supply air to the carbureter which supplies inflammable gas to the burners under the steam-boiler, and optionally, in addition thereto, to devices for heating or illuminating purposes, in connection with the machinery or the structure to which it is attached or allied.

In the drawings, the improvement is shown as applied to a locomotive steam-engine, though the invention is not limited to locomotives, but is applicable to stationary engines.

The use of a fluid hydrocarbon having become general in many of the arts, and adapted to many mechanical uses, I have sought for a plan of making it available for generating steam for a motor. For this purpose I attach an air-pump, or some other air-forcing apparatus, to some moving part of the machinery, by means of which air is driven through a carbureter for the supply of inflammable gas as fuel for the use of the boiler, or for other calorific or photic uses.

The piston air-pump is shown as an illustration, but any other form of air-forcing apparatus may be employed.

In the drawings, A is the boiler, and B B B vertical tubes therein. C is the steam-jacket around the boiler proper, the fire-chamber, and steam-space. D is the steam-dome. The boiler and engine are mounted on a frame, F, and wheels G.

H is the cylinder; Q, the piston-rod; P, the

slides; N, the pump-rod; I, the force-pumps, by which air is injected through pipes J into the chamber K, from which it passes, by the pipe R, into the chamber L, in which the hydrocarbon fluid is contained. The ordinary atmospheric air, which passes through the fluid in L, becomes carbureted and inflammable, and passes by the pipe M to the burners, which are situated under the boiler in any required position, number, or size. I have shown them as each underneath a vertical flue, which has a central spherical enlargement, and discharging the heated and uninflammable gases resulting from combustion into the chamber O, and thence, by the chimney E, into the open air.

A safety-valve, O, on the air-chamber K provides egress for the air in said chamber when it has attained a certain pressure.

I have shown the application of my improvement to a locomotive-engine; but I do not limit myself to any particular form of boiler, engine, air-pump, carbureter, or burner.

The carbureter and pump may be consolidated in some manner. I speak of them by their functions, not as necessarily detached portions. The essential functions are the engine, air-forcing apparatus, carbureter, and boiler, with or without a compressed-air chamber, and the conduction of inflammable gas to other parts of the apparatus or structure for calorific or photic purposes.

A pipe from the carbureter may conduct the carbureted air to other locations in connection with the engine, such as the requisite lighting and heating arrangements of the train of cars, or the buildings in connection with the engine.

Having described my invention, what I claim therein as new, and desire to secure by Letters Patent, is—

1. The combination of an air-forcing apparatus and carbureter with the engine and the boiler, for the purpose described.

2. In combination with the engine, air-forcing apparatus, carbureter, and boiler, the chamber for reserve of compressed air, as and for the purpose described.

3. The boiler-tubes, constructed with a spherical or equivalent enlargement, as and for the purpose described.

ELIAS S. HUTCHINSON.
